(57) **CLAIM**

The ornamental design for a modular fluid retention and management tray, as shown and described.

DESCRIPTION

FIG. 1 is a top perspective view of a modular fluid retention and management tray.

FIG. 2 is bottom perspective view of the tray of FIG. 1.

FIG. 3 is a top view of the tray of FIG. 1.

FIG. 4 is a front elevation view of the tray of FIG. 1, the rear elevation view is a mirror image of the front elevation view. FIG. 5 is a right-side elevation view of the tray of FIG. 1, the left side elevation view is a mirror image of the right-side elevation view; and,

FIG. 6 is a bottom view of the tray of FIG. 1.

The broken line showing portions of the tray is included for the purpose of illustrating environment and forms no part of the claimed design.

1 Claim, 5 Drawing Sheets
